DESIGN FOR A FLOWER RECEPTACLE

Melvin C. Rau, Milwaukee, Wis.

Application April 3, 1935, Serial No. 56,187

Term of patent 14 years

To all whom it may concern:

Be it known that I, Melvin C. Rau, a citizen of the United States, residing at Milwaukee, in the county of Milwaukee and State of Wisconsin, have invented a new, original, and ornamental Design for Flower Receptacles, of which the following is a specification, reference being had to the accompanying drawing, forming part thereof.

Figure 1 is a plan view of a flower receptacle, showing my new design.

Fig. 2 is a side view of the same.

Fig. 3 is a view in perspective.

I claim:

The ornamental design for a flower receptacle, as shown.

MELVIN C. RAU.
